UNITED STATES PATENT OFFICE.

DE LANCEY A. CAMERON, OF GENESEO, NEW YORK, ASSIGNOR TO DELAC PLASTER CO.,
OF MUMFORD, NEW YORK, A CORPORATION OF NEW YORK.

PLASTER-BOARD.

1,129,637.

Specification of Letters Patent. Patented Feb. 23, 1915.

Application filed May 20, 1911. Serial No. 628,568.

To all whom it may concern:

Be it known that I, DE LANCEY A. CAMERON, a citizen of the United States, and resident of Geneseo, in the county of Livingston 5 and State of New York, have invented certain new and useful Improvements in Plaster-Boards, of which the following is a specification.

This invention relates to boards of plastic 10 composition, such as are employed in buildings in place of plaster spread upon lathing.

It has been previously proposed to employ 15 reinforcements of wire netting in plasterboards as, for example, in my own prior application filed August 4, 1909, Serial No. 511,209, but it has been found that such reinforcements do not sufficiently strengthen the 20 edges of the boards, so that when the boards are carelessly handled, or when they are being nailed in place, these edges tend to crack and to crumble away, particularly around the nails.

One object of the present invention, therefore, is to produce a plaster-board in which 25 the edges are strengthened by a reinforcement of peculiar form, this reinforcement extending along, and being substantially co-extensive with, the edges, while the remainder of the plaster-board may be constructed 30 and reinforced in any usual or suitable manner.

A further object of the invention is to provide for coöperation between this marginal reinforcement and the nails, or other 35 fastening devices by which the plaster-board is secured in place, and to this end I provide the marginal reinforcement with nail-engaging eyes, and also provide indications 40 upon the face of the plaster-board to designate the positions of these eyes, so that the nails may be properly engaged therewith.

Other objects and features of the invention will be set forth in connection with the 45 following description of the illustrated embodiment thereof.

In the accompanying drawings: Figure 1 is a front-elevation of a plaster-board embodying the present invention, with a portion shown in section to reveal the interior 50 construction; and Fig. 2 is a vertical section, on a larger scale, on the line 2-2 in Fig. 1.

The plaster-board illustrated in the drawings is of the usual general form, being 55 rectangular and of uniform thickness, and

of such dimensions that when applied to the studding of a building it will extend across two of the spaces between adjacent studs. Obviously the dimensions and proportions of the board may be varied at will, however. 60 The composition of the body 3 of the board is not an essential feature of the present invention, but it preferably includes a plastic base, such as plaster of Paris, mingled with fiber and with saw-dust or other filling material. 65 A suitable composition for this purpose is disclosed in my application hereinbefore referred to. The board is preferable formed with a smooth face 4, which requires no further finishing except the application of paint or wall-paper, or other 70 coating.

The body of the board is reinforced in the usual manner by means of light wires in the form of netting. As illustrated, this body-reinforcement comprises horizontal straight wires 5 and connecting wires 6 wound about the wires 5. I find this form of netting to be particularly effective as it affords wires 75 extending directly between the studs so as 80 to directly resist strains in a horizontal direction. This netting is embedded in the body of the board in the process of manufacture.

The present invention resides particularly 85 in the novel manner in which the marginal portions of the board are reinforced. For this purpose I employ a comparatively heavy wire 7 which is embedded in the body close to, and substantially parallel with, the 90 edges of the board. This wire has, therefore, a generally-rectangular form, and its ends 8 are joined in any convenient manner as, for example, by twisting them together. Obviously this rectangular reinforcement 95 may be coextensive with the entire board, thus producing a single integral panel, but for convenience in dividing the board when necessary the marginal reinforcement is 100 preferably made in two or more rectangular sections, as shown in Fig. 1, so as to divide the boards into two or more panels and produce a diametral space 12 in which the board may be cut without the necessity of severing the wire 7.

As this diametral space comes at the point where the board engages a stud when the board is used without division, it is not necessary that the board be as strong at this point as at intermediate portions. The netting by which the 105 110

body of the board is reinforced may be connected at intervals with the marginal reinforcement, although this is not essential. As shown in Fig. 1, the ends of some of the 5 horizontal wires 5 are twisted about the wires 7.

In order that the marginal reinforcements may serve not only to strengthen the edges of the boards, but also as anchorages for the 10 nails by which the board is fixed in place, the wire 7 is provided at intervals with looped portions 9 forming eyes through which the nails may be driven. These eyes are located at the corners of the board and 15 also at the vertical diameter where the board is nailed to an intermediate stud. In order to insure the driving of the nails at the proper points to engage the eyes, the surface of the board is marked in some way, and 20 this may be done conveniently by providing a perforation 10 in the body registering with each eye. This perforation also facilitates the driving of the nails and reduces the liability of splitting in consequence, although 25 it is not necessary for this purpose if the body is suitably strengthened with fiber. On the face of the board the perforation may have an enlarged portion 11 to receive the nail-head, although this also is not es- 30 sential as the composition may be sufficiently yielding to permit the nail-head to seat itself without such recess. For the further reinforcement of the board, and also to provide intermediate nail-anchorages 35 on the vertical edges, I employ additional reinforcing wires 13 which are formed as elongated horizontally-arranged rectangles provided with nail-receiving eyes 14 at their corners. This arrangement also permits the 40 board to be divided horizontally when necessary, and when so divided the wires 13 constitute marginal reinforcements for the intermediate horizontal edges of the severed portions. 45 An important advantage of the novel form of reinforcement hereinbefore described resides in the fact that the heavy wires run not only parallel with the studs upon which the boards are mounted but also

directly from one stud to the next, being 50 secured firmly to each stud by nails or other fastenings. For this reason any tendency to relative movement in the studs is resisted without strain upon the body of the board, so that the frame of the building is stiffened, 55 while pulling apart of the edges of the boards at the joints is effectually prevented. This feature makes the board particularly valuable for outside use as well as inside use.

My invention is not limited to the embodiment thereof hereinbefore described and illustrated in the accompanying drawings, but may be embodied in various forms within the nature of the invention as it is defined in the following claims. 60

I claim:

1. A plaster-board having, in combination, a rectangular body of plastic composition, and reinforcements embedded therein and comprising wires arranged continuously in substantially rectangular form, each reinforcement extending along, close to, and parallel with, at least two edges of the body and thence through the body close to and parallel with a diameter of the body, 70 so that the body may be divided into a plurality of similar rectangular panels having continuous marginal reinforcements.

2. A plaster-board having, in combination, a rectangular body of plastic composition, and reinforcements embedded therein and comprising wires arranged in substantially rectangular form, each reinforcement extending along, close to, and parallel with, at least two edges of the body and 80 thence through the body close to and parallel with a diameter thereof, so that the body may be divided into a plurality of similar rectangular panels having continuous marginal reinforcements, said reinforcements being provided, at their exterior and interior corners, with nail-receiving 85 anchorages.

DE LANCEY A. CAMERON.
